UNITED STATES PATENT OFFICE.

ELI T. STARR, OF PHILADELPHIA, PA., ASSIGNOR TO JAMES W. WHITE, JAMES CLARENCE WHITE, AND H. M. LEWIS, TRUSTEES, OF SAME PLACE.

DENTAL DRILL.

SPECIFICATION forming part of Letters Patent No. 276,921, dated May 1, 1883.

Application filed April 30, 1881. (No model.)

To all whom it may concern:

Be it known that I, ELI T. STARR, of the city and county of Philadelphia, in the State of Pennsylvania, have invented certain new and useful Improvements in Dental-Engine Hand-Pieces and Operating-Tools, of which the following is a specification.

My present invention relates to an improved hand-piece of the type shown in my Letters Patent Nos. 233,708 and 233,709, of October 26, 1880.

The objects of my present invention are, first, to improve the construction of the hand-piece, so that wear of the spindle-chuck and of its bearings may be readily compensated for, and unsteady movements or wabbling of said chuck in its bearings be prevented without interfering with the free rotation of the chuck upon its longitudinal axis; secondly, to improve the organization of the tool-locking devices of the spindle-chuck, so as to permit rapid and easy insertion of the operating-tools in and their ready removal from the socket of the chuck, while firmly and securely locking said tools in said socket as against endwise movement when at work; and, thirdly, to improve the construction of the shanks of the operating-tools, so that they may be accurately centered in the chuck-socket, and so that wear of the tool-shanks and of the chuck-socket may be compensated, in order to prevent all unsteady motion or lateral vibration of the tools in the socket of the chuck while at work, whereby dental operations may be performed with greater ease, nicety, and skill than heretofore, with a considerable saving of time to the operator and the avoidance of noise disagreeable to the patient.

The subject-matter claimed is recited at the close of the specification.

The accompanying drawings represent my present improvements as organized in the best way now known to me.

Figure 1 is a view in elevation of my improved hand-piece on an enlarged scale, and Fig. 2 is a longitudinal central section therethrough on the line 2 2 of Fig. 1. Fig 3 is a view, partly in section, of a portion of the spindle-chuck, the operating-tool, and the tool-locking devices and their controlling-sleeve, the scale being still larger than that of Figs.

1 and 2. Fig. 4 is a cross-section through the chuck and tool-shank on the line 4 4 of Fig. 3. Fig. 5 is a view of the improved tool on a largely-magnified scale. Fig. 6 is a view of a cylindrical tool-shank having a plain flattened driving end; and Figs. 7 and 8 are modifications of the tool shown in Figs. 2 and 5.

The hand-piece casing A is shown in this example as constructed of four tubular sections—that is to say, it is shown as consisting, first, of a handle-section, a, having preferably a detachable hard-metal nose, which gives bearing to and envelops the front end of the spindle-chuck or tool-holder B; second, of a section, a', to which the handle-section a is detachably connected—by screw-threads preferably—said section a' affording the bearing for the rear end of the spindle-chuck; third, of a section, a², which is detachably connected with the butt-end of section a'—by screw-threads preferably—so as to permit disconnection of said sections a' a², to permit access to the adjustable cone-collar b on the rear end of the spindle-chuck B; and, fourth, of a shank-section, a³, which is connected with the section a² by a swivel-joint, a⁴, of well known construction, in order to permit the handle-section, which is grasped by the hand, (being ordinarily held centrally of the fingers and thumb of the operator; somewhat after the fashion of holding a pen or pencil,) to be turned relatively to said shank-section around the spindle-chuck, so as to conform to the turning movements of the operator's hand in manipulating the tool.

In order to prevent accidental unscrewing of the handle-section a or the casing-section a² from the intermediate casing-section, a', while permitting their ready disconnection when desired, I employ a slide, C, fitting a longitudinal groove, c, in the exterior of the section a', and also fitting corresponding grooves or recesses in the flanges c' c², respectively, of the handle-section a and casing-section a², as clearly shown in Figs. 1 and 2. This slide C is slotted longitudinally for the passage of a screw, for example, which holds the slide in the groove in casing-section a', while permitting it to move endwise to a limited extent. When the slide is in the position shown in Figs. 1 and 2 it will be obvious that neither the handle-section a nor the casing-section a² can be un-

screwed from the casing-section a' , while if moved endwise to carry it out of the groove of either said handle-section a or said section a' the disconnection of the free section may be 5 readily accomplished. The slide is provided on its upper face with cross ribs or grooves, so that the thumb-nail may be applied to readily move it. The shank-section a^3 of the casing A is connected, in the usual way, with the 10 outer or free end of a flexible sheath or tube, while the butt-end of the spindle-chuck or tool-holder B is connected, in the usual way, with the 15 outer or free end of a flexible driving-shaft or power-conveyer enveloped by the before-mentioned sheath or tube, the inner end of said flexible shaft being connected with a driven spindle or shaft of the engine to receive motion therefrom, so as to impart a rapid revolving motion to the spindle-chuck in its 20 bearing in the hand-piece casing. The said flexible enveloping sheath or tube and said flexible shaft or power-conveyer may be similar to those in common use, or to those shown in Letters Patent heretofore granted to me 25 September 2, 1879, and November 25, 1879, numbered respectively 219,320 and 222,093; but as neither said sheath and shaft nor the particular organization of engine employed constitute the subject-matter claimed by me 30 herein, it is unnecessary to illustrate them in the drawings or describe them herein in detail. The front end of the spindle-chuck B is socketed for the reception of the shanks of the operating-tools, as usual, and has its bearing in 35 the nose of the handle-section a of the casing A, while the rear end of the chuck is extended through the section a' , so as to have its rear bearing therein. A collar or ring, b , having a tapering or cone end, is screwed upon a 40 male screw, b' , formed upon the rear end of the spindle-chuck, so as to be adjustable, and so as to fit with its cone end in a correspondingly-formed seat in the butt-end of the casing-section a' , the collar being locked to the 45 spindle, when properly adjusted, by a set-screw, b^2 , as clearly shown in Fig. 2. Said adjustable cone-collar b constitutes the pull-journal of the spindle-chuck—that is to say, it 50 constitutes a surface or journal which prevents the endwise forward movement of the chuck in the casing when a pulling or "draw" cut is being made with the operating-tool.

A friction-collar, b^3 , externally tapered at 55 its rear end, is fitted upon the spindle-chuck, so as to fit with its tapered or conical butt-end into a corresponding seat in the front end of the casing-section a' . The friction-collar b^3 is held to its seat in the casing-section a' by a collar, b^4 , fitting the spindle, and having a 60 tapering or conical butt-end which fits a corresponding seat in the front end of said friction-collar, the cone-collar b^4 being locked to the spindle by a set-screw, for example, as 65 clearly shown in Fig. 2. Said cone-collar b^4 constitutes the thrust journal or surface of the chuck—that is to say, it constitutes a journal or surface which prevents the endwise back-

ward or inward movement of the chuck in the casing when a pushing or thrust cut is being made with the operating-tool.

It will be seen that no endwise movement of the spindle-chuck can take place in the casing, while as wear occurs between the parts it can be readily taken up or compensated for by the adjustment of the cone-collar b , above described.

The several collars b^3 b^4 are made detachable, so as to be readily renewed when required.

The conical supplemental friction-collar b^3 is preferably made of hard metal, as also the cone-collars b^4 . Said friction-collar protects the casing-section a' from wear due to the thrust of the chuck, inasmuch as it is prevented from turning with the chuck by the friction between its externally-tapered or conical butt-end and said case-section, and thereby receives the thrust and wear instead of the case-section.

By the employment of the loose friction-collar not only is wear of the casing-section a' prevented, but the ready substitution of a new thrust-bearing or friction-collar in place of one which has become too much worn is permitted. This construction avoids the necessity, in order to prevent wear of the casing-section which is to sustain the thrust of the chuck, of a fixed steel facing fastened in and forming an integral part of said section, as shown in the patent of Cushing, No. 218,239, of August 5, 1879, for instance.

It will be observed that a chamber, d , is formed between the front end of the spindle-chuck and the end of the casing-nose, through which the tool-shank is inserted on its way to the chuck-socket, and this is for the purpose of arresting the passage into the front bearing and chuck-socket of saliva, grit, &c., taken up by the revolution of the tool; and, furthermore, to prevent the exudation of oil from the front bearing to soil the fingers of the operator or face of the patient; but as this is the invention of Dr. Phillips, heretofore patented to him, it of course is not claimed as of my invention.

The shank of the operating-tool E, adapted to my improved hand-piece, is a straight cylindrical shank having an annular groove, e , and in rear thereof provided with a tapered surface, e' , to fit a corresponding surface in the chuck-socket, so as to center the tool in the socket and make it fit firmly therein. The butt-end of the shank is cut away or flattened, as at e^2 , so as to have a flat or beveled driving-surface, which is acted upon by a suitable lug, pin, or actuator, d' , in the socket of the chuck. The front end of the tool terminates in the usual operating-point, which may be in the form of a cutting-burr, drill, slotter, disk, or other working-point.

The groove e in the tool-shank is preferably a concave one, and is for the engagement of the devices which lock the shank in the socket of the chuck as against endwise movement.

This groove is peculiar, in that it forms a notch or recess for the engagement of the tool-locking devices, so formed that its rear wall, e^3 , is inclined, tapering from the cylindrical surface 5 of the shank in a forward direction, so that when acted upon by laterally-moving tool-locking devices the tool will be moved or wedged backward by reason of its inclined wall, and the tapered surface e' crowded firmly into its 10 corresponding seat in the chuck-socket.

In practice I contemplate constructing the operating-tool either in a single piece or in sections, as shown in Fig. 5, one section consisting of the peculiarly-formed cylindrical shank, 15 and the other of the operating-point, with a short shank or extension fitting a socket in the front end of the cylindrical portion, the two sections of the tool being rigidly united, for instance, by a transverse pin or rivet, or 20 by solder.

In Figs. 7 and 8 of the drawings I have shown a modification of the tool depicted in Figs. 2 and 5, in that the tapering surface e' is formed at the extreme end of the tool-shank, 25 instead of just in front of its flattened driving-surface e^2 .

The cylindrical portion of the tool-shank fits snugly the opening in the nose of the hand-piece, through which the shank is passed on 30 its way to the chuck-socket, while, as before stated, the tapered surface e' of the shank fits a corresponding surface in the chuck-socket. The tool is positively driven, when inserted in the socket of the chuck, by the pin or lug d' , 35 crossing or extending into said socket and engaging the flattened driving-surface of the tool, while the tool is locked from endwise movement or withdrawal by the tool-locking devices, consisting of three plate-springs, F F F, 40 arranged around the chuck at equal distances apart, as shown in Fig. 4. The locking springs lie in longitudinal recesses in the chuck, and are secured therein, at their rear ends, by any suitable arrangement. Said springs are so 45 constructed as to have a tendency at their front ends to move outward or laterally when not compressed by a sleeve or thimble, G, surrounding the chuck, and movable endwise thereon.

The front laterally-movable ends of the three locking-springs are each provided with a preferably tapered, inclined, or cam lug, f , projecting into a lateral opening intersecting the bore or socket of the chuck, and each lug 50 comes in contact, when compressed, with the inclined wall of the locking groove or notch in the tool-shank, and thereby, as the lugs are forced down into the groove, forces the tool backward and crowds or draws its tapered surface 55 firmly into its seat in the chuck-socket, whereby the tool is not only firmly locked from withdrawal, but is also accurately centered in the socket and prevented from wobbling or rattling therein. Any wear that may occur 60 between the tool and the socket is also compensated for, and the tool always driven firmly and without rattling or loose movement.

I have found that the simplest way of forming the inclined locking groove or notch e in the tool-shank is to make the groove concave, 70 as shown; and I have also found that the three springs, arranged around the chuck at equal distances apart, are more advantageous than two springs, such as shown in my aforesaid Patent No. 233,709. Instead of forming the locking-groove e with an inclined rear wall, the groove 75 may be a plain annular one, in which case it will be found that the action of the cam-lugs f of the springs F on the edge of the rear wall of the groove will cam or crowd the tool into 80 the socket.

The sleeve G is thrust forward to compress the lug-ended tool-locking springs by means of a coiled spring, H, also surrounding the tool-holder or chuck, and compressed between 85 the fixed collar b^4 at rear and the annular shoulder formed by the butt-end of the sleeve at front, the force of said spring H being at all times exerted to thrust the sleeve forward to compress the laterally-yielding locking devices into engagement with the grooved tool-shank, as clearly shown in Fig. 2.

When a tool has been inserted and locked in the socket, and it is desired to remove it, the sleeve G is retracted against the force of 90 the spring H, so as to permit the locking ends of the springs F to move outward, which operation releases the tool and enables it to be withdrawn. This retraction of the sleeve I preferably accomplish by means of a lever or 95 finger-piece, I, pivoted between suitable lugs on the exterior of the casing, the front end of the lever being provided with a lip or extended end, i , which works through an opening, h , in the side of the casing, and engages, when the 100 rear end of the lever is raised, with an annular shoulder on the sleeve to retract the sleeve as the lip i moves backward around the pivot 105 of the lever.

The lever, when not raised to manipulate 110 the tool-locking devices, lies down about parallel with the casing, (see Figs. 1 and 2,) so that its lip remains out of the way of the sleeve G, and does not interfere with the turning movements of said sleeve with the spindle-chuck when the tool is at work.

I have so organized the lever I, which actuates the tool-locking devices, that it is raised in a forward direction and moves the controlling-sleeve G backward to permit the tool-locking devices to move laterally to release the tool, and this capacity of the lever to be lifted or rocked upward and forward to operate the tool-locking devices is a very valuable one in the manipulation of a dental-engine 120 hand-piece, rendering its operation easy and rapid, enabling the thumb of the hand that holds the hand-piece to be used to work the lever with great ease, while the other hand is at the same time free to remove or insert the tool. 125 The lever is also so organized as not to interfere with the ready disconnection of the handle-section of the casing.

I disclaim herein the subject-matter claimed

in my aforesaid Letters Patent Nos. 233,708 and 233,709.

I claim herein as my invention—

1. The combination, substantially as hereinbefore set forth, of the casing, the spindle-chuck, the adjustable cone-collar constituting the pull journal or surface of the chuck, the cone-collar constituting the thrust journal or surface of said chuck, and the conical friction-collar interposed between said thrust-collar and the casing to receive the thrust of the chuck.

15 2. As a new article of manufacture, a friction-collar to receive the thrust of a revolving spindle, having a tapering external surface at one end and a tapering internal surface at the opposite end.

3. The hand-piece casing constructed, substantially as hereinbefore set forth, of three detachable tubular sections, in combination with a slide carried by one of said sections to prevent their accidental separation, while adjustable to permit the sections to be readily disconnected.

25 4. The combination, substantially as herein-before set forth, of the casing, the spindle-

chuck, the three lug-ended tool-locking springs arranged at substantially equal distances apart around said chuck, so as to act upon the inclined wall of the locking-groove of a tool-shank, the sleeve to compress said springs, the spring acting to thrust said sleeve forward, and the external lever to retract said sleeve to permit the locking ends of the springs to move outward.

5. The improved operating-tool, constructed substantially as hereinbefore set forth, having the following characteristics: first, a cylindrical shank, having an annular groove or recess therein for the engagement of the tool-locking devices; second, a tapering surface in rear of said groove or recess to fit a corresponding seat in a chuck-socket; and, third, a flattened or beveled driving-surface to engage the driving-surface of the chuck-socket. 45

In testimony whereof I have hereunto subscribed my name.

ELI T. STARR.
